UNITED STATES PATENT OFFICE.

AMAND PAPE, OF WILLOW SPRINGS, ILLINOIS.

APPARATUS FOR SEALING BOXES.

1,422,300.

Specification of Letters Patent. Patented July 11, 1922.

Application filed April 9, 1920. Serial No. 372,451.

To all whom it may concern:

Be it known that I, AMAND PAPE, a citizen of the United States, and a resident of Willow Springs, in the county of Cook and 5 State of Illinois, have invented certain new and useful Improvements in Apparatus for Sealing Boxes, of which the following is a full, clear, and exact description.

The invention relates to apparatus for 10 sealing boxes.

The object of the invention is to provide an apparatus which is adapted to seal the boxes in transit therethrough.

Another object of the invention is to provide improved apparatus for this purpose in which the flap-holding or controlling elements are stationary and act on the boxes as they are conveyed through the apparatus.

Another object of the invention is to provide apparatus for sealing boxes which is simple in construction and efficient in operation.

The invention consists in the several novel features hereinafter set forth and more particularly defined by claims at the conclusion 25 hereof.

In the drawings: Fig. 1 is a side elevation of an apparatus embodying the invention. Fig. 2 is a plan. Fig. 3 is a central longitudinal section. Fig. 4 is a transverse section on line 4—4 of Fig. 3. Fig. 5 is a transverse section on line 5—5 of Fig. 3. Fig. 6 is a transverse section on line 6—6 of Fig. 3.

Cross-shafts 8 are mounted on a supporting-frame 7 adjacent the ends of the frame respectively. Sprockets 10 and 11 are mounted on these shafts to operate endless chains 12 which are provided with pushers or flights 13, and this mechanism serves as 35 an endless conveyor for pushing boxes 14 in longitudinal succession along the frame. Shaft 9 is provided with a belt pulley 15 for driving the conveyor. The upper reaches of the endless-chains 12 are supported and 40 run on the frame and are held thereon by angle-iron bars 16 which are secured to, and in spaced relation to the frame by strips 17. The vertical flanges of bars 16 are spaced apart according to the width of the boxes 45 14 which are guided between them as they are advanced by the conveyor.

The invention is more particularly adapted for sealing boxes which are adapted to hold a number of cans or other articles, 55 which are usually formed of corrugated board, and comprise sides and ends which

have been secured together before the boxes are filled, end flaps 14^a adapted to be turned inwardly, and side-flaps 14^b adapted to be turned inwardly to lap the end-flaps and 60 close the top and bottom of the box. These boxes are placed upon the endless conveyor adjacent the shaft 8 and between the guide-bars 16, with the lower corners of the box resting upon the chains 12 so that the 65 flights 13, as they encounter the boxes, will feed them forwardly. When these boxes are placed on the conveyor, the lower end-flaps 14^a will be held in substantially horizontal position by the side flaps 14^b which 70 will be held slightly inturned by the chains 12. The upper end-flaps will be folded inwardly and the upper side flanges 14^b will be free, usually extending upwardly, as indicated in dotted lines in Fig. 4. As each 75 box is advanced by the conveyor, its lower flaps 14^a will be held and guided by stationary holder-plates 18 so that the flaps cannot spring downwardly. A roll 19 is mounted to rotate in and receive suitable adhesive 80 from a tank 20 and to apply the adhesive to the central portions of the underside of the end-flaps 14^a as the boxes move over said roll. The lower side-flaps 14^b are folded outwardly and downwardly by stationary 85 deflectors 21 so these flaps will clear the reservoir 20 and be separated from the flaps 14^a while the adhesive is being applied to the latter. After the adhesive has been applied to the underside of the lower end-flaps 90 14^a, the lower side-flaps 14^b will pass off the deflector 21 and engage the stationary 95 folder-strips 22 which are convergent and adapted to engage the outer side of flaps 14^b to force them upwardly to bring their 100 edges together on the central line of the box and to cause their margins to engage the adhesive on the lower flaps 14^a. The folder-strips 22 are secured to a cross-bar 23 which is suitably supported by brackets 24 fixed 105 to the frame 7. The upper side-flaps 14^b pass under deflectors 26 which are formed to swing said flaps outwardly into substantially horizontal position, as shown in Fig. 4, and while so held they will pass under 110 brushes 27 which apply a coat of adhesive to the inner faces of the margins of said flaps. While under the deflectors 26, said flaps will be held against downward movement by shoulders 28 on the bars 29 which are secured to the frame 7 and support said deflectors and also the reservoir 20. An ad-

hesive reservoir 30 is provided for each brush 27. The brushes are pivoted, as at 31, and inclined to permit the upper side flaps to lift the brushes as they pass under them. A spring 32 is applied to each brush to retract it and to press it into contact with the flaps. As the upper flaps 14^b leave the brushes, they pass onto stationary folders 33 which are formed, as at 33^a, to first swing 10 said flaps upwardly and inwardly and as at 34 to thereafter force the flaps downwardly into contact with the upper end-flaps 14^a to cause them to stick together where the adhesive has been applied to the 15 side-flaps.

While the boxes with the upper and lower flaps sealed are held between the folders 22 and 33 and before they leave the endless conveyor, they pass between a series of rollers to hold the flaps closed until the adhesive has set. For this purpose, a frame consisting of bars 37 and posts 38 is mounted upon brackets 24 and standards 39, and lower horizontal rollers 40 and upper horizontal rollers 41 are mounted in longitudinal series to engage the tops and bottoms of the boxes and hold the flaps closed, and longitudinal series of vertical rollers 42 are mounted to engage the sides of the boxes. 25 30 The lower horizontal rollers 40 are extended beyond the upper rollers and side rollers to form a table or support from which the sealed boxes may be readily removed.

In operation, it is only necessary for the operator to successively place the boxes on the endless conveyor. As the flights 13 encounter the boxes, they will positively advance them longitudinally of the folding and adhesive-applying devices and the folding and sealing of the flaps will be effected while the boxes are in transit. Before the boxes are released from the endless conveyor, they will have passed between the retaining rolls. The succeeding boxes will 40 45 force the previously sealed boxes through the retaining rolls whereby the sealed flaps will be held until the adhesive has set.

The invention exemplifies an improved apparatus or machine for sealing boxes in which the deflecting and folding elements for the flaps are stationary, in which the boxes are successively brought into cooperative relation with said elements, and in which the sealing is effected while the boxes 50 55 are carried through the machine by an endless conveyor.

The invention is not to be understood as restricted to the details set forth, since these may be modified within the scope of the appended claims, without departing from the spirit and scope of the invention.

Having thus described the invention, what I claim as new and desire to secure by Letters Patent, is:

65 1. In a box sealing machine, the combina-

tion of a conveyor adapted to receive and successively advance filled boxes and comprising members underlying the side margins of the box and formed to leave the intermediate portions of the bottom of the box exposed with the bottom flaps between them, and means for folding the bottom flaps upwardly and between said members and securing them to seal the bottom of the box.

75

2. In a box sealing machine, the combination of a conveyor adapted to receive and successively advance filled boxes and comprising members underlying the side margins of the box and formed to leave the intermediate portions of the bottom of the box exposed with the bottom flaps between them, means for applying an adhesive to the bottom of the box between said conveyor members, and means for folding and pressing the bottom flaps to seal them to close the bottom of the box while the boxes are being advanced by the conveyor.

80

85

3. In a box sealing machine, the combination of a conveyor adapted to receive and successively advance filled boxes and comprising members underlying the side margins of the box and formed to leave the intermediate portions of the bottom of the box exposed with the bottom flaps between them, means for applying an adhesive to the bottom of the box between said conveyor members, and means for simultaneously folding and pressing the bottom flaps to seal them to close the bottom of the box while the boxes are being advanced by the conveyor.

90

95

4. In a box sealing machine, the combination of a conveyor adapted to receive and successively advance filled boxes and comprising members underlying the side margins of the boxes and formed to leave the intermediate portions of the bottom of the box exposed with the bottom flaps between them, means to apply adhesive to the bottom of the box between the conveyor members, means for deflecting the bottom flaps while disposed between the conveyor members outwardly to clear the sealing means, and means for folding said flaps against the bottom to seal them after they have passed said sealing means.

105

110

115

120

125

5. In a box sealing machine, the combination of a conveyor adapted to receive and successively advance filled boxes and comprising members underlying the side margins of the box and formed to leave the intermediate portions of the bottom of the box exposed with the bottom flaps between them, means for applying an adhesive to the bottom of the box between said conveyor members, and stationary means for folding and pressing the bottom flaps to seal them to close the bottom of the box while the boxes are being advanced by the conveyor.

130

6. In a box sealing machine, the combination of a conveyor adapted to receive and successively advance filled boxes and comprising members underlying the side margins of the box and formed to leave the intermediate portions of the bottom of the box exposed with the bottom flaps between them, means to apply an adhesive to the bottom of the box between the conveyor members, stationary means for deflecting the bottom flaps while disposed between the conveyor members outwardly to clear the sealing means, and stationary means for folding said flaps against the bottom to seal them after they have passed said sealing means. 30
7. In a box sealing machine, the combination of a conveyor adapted to successively advance boxes provided with upper side flaps, means to fold said flaps outwardly, means to apply adhesive to said flaps mounted to be shifted thereby, and means for closing said flaps. 35
8. In a box sealing machine, the combination of a conveyor adapted to successively 40
- 45
- advance boxes provided with upper side flaps, means for folding said flaps outwardly, pivotally sustained adhesive applying means adapted to be shifted by said flaps and means for closing the flaps after the adhesive has been applied.
9. In a box sealing machine, the combination of a conveyor adapted to successively advance boxes provided with side and end flaps, centrally disposed means for applying adhesive to the end-flaps, means to deflect the side-flaps around said applying-means, and means for closing the side-flaps after the adhesive has been applied.
10. In a box-sealing machine, the combination of a conveyor adapted to successively advance boxes provided with side and end flaps, centrally disposed means for applying adhesive to end-flaps, stationary means to deflect the side-flaps around the applying means, and stationary means for closing the side-flaps after the adhesive has been applied.

AMAND PAPE.
